CLAIM

The ornamental design for a display screen with a graphical user interface, as shown and described.

DESCRIPTION

FIG. 1 is a front view of a display screen with a graphical user interface, showing the new design in a first embodiment;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The appearance of the animated images sequentially transition between the images shown in FIGS. 1 through 6. The process or period in which one image transitions into another forms no part of the claimed design.

The outermost broken lines illustrated a mobile device, which is the environment of the design and forms no part of

(Continued)

the claim. The remaining broken lines illustrate a display screen and portions of the graphical user interface that form no part of the claimed design.
